UNITED STATES PATENT OFFICE.

ARTHUR C. WHEELOCK, OF OAKLAND, CALIFORNIA.

WASHING AND DRYING MACHINE.

1,413,882.

Specification of Letters Patent: Patented Apr. 25, 1922.

Application filed November 19, 1920. Serial No. 425,163.

To all whom it may concern:

Be it known that I, ARTHUR C. WHEELOCK, a citizen of the United States, and a resident of Oakland, county of Alameda, 5 and State of California, have invented a new and useful Washing and Drying Machine, of which the following is a specification.

My invention relates to a washing machine of the rotating cylinder type which may be used for drying the articles operated upon as well as washing them.

An object of the invention is to provide a laundering machine of the type mentioned 15 in which the cylinder is adapted to be rotated both for the drying and washing purposes.

Another object of the invention is to provide a washing and drying machine in 20 which the cylinder will be caused to rotate only when it properly occupies either the drying or washing positions.

A further object of the invention is to provide a machine in which the cylinder 25 during the drying operation will be rotated at a much greater speed than during the washing operation.

A still further object and one of the most important of the invention is to provide 30 a machine in which the cleansing liquid will be caused to flow through the cylinder in a manner such as will enable the articles therein to be most effectively washed at a minimum expenditure of time 35 and energy.

The invention possesses other objects and features of advantage, some of which, with the foregoing, will be set forth in the following description of the preferred form of 40 my invention which is illustrated in the drawings accompanying and forming part of the specification. It is to be understood that I do not limit myself to the showing made by the said drawings and description, 45 as I may adopt variations of the preferred form within the scope of my invention as set forth in the claims.

Referring to said drawings:

Figure 1 is a vertical sectional view of the 50 machine showing the cylinder in the washing position.

Figure 2 is a horizontal section taken on the line 2-2 of Figure 1, the removable rack shown in the succeeding figure being 55 indicated in dotted lines.

Figure 3 is a side elevation of the removable rack.

Briefly expressed the machine in its present embodiment comprises a tank in which the cleansing liquid is adapted to be contained, a cylinder arranged in the tank and rotatable on a vertical axis, suitable means for holding the cylinder suspended in the tank at different heights, means for rotating the cylinder at a greater speed 65 in one position of suspension than in another, means for retarding the speed of rotation of the cylinder as it is moved from one position to another, means for moving the cylinder from one position to another, 70 and means for locking the cylinder when properly positioned and for causing said cylinder rotating means to be driven only when the cylinder is so positioned. The cylinder as here shown in general terms 75 comprises perforated side walls, a substantially imperforate bottom end wall, and a tubular perforated conduit concentrically arranged within the cylinder and extending through said end wall.

A detailed description of my invention follows:

The machine as here illustrated comprises a cylindrical tank 2 having an opening 3 at the top thereof preferably provided with a suitable cover 4 which may be removed when access to the interior of the tank is desired. Arranged within the tank 2 and preferably suspended from the spider 5, in a manner which will presently be described, is a receptacle or cylinder 7 adapted to rotate about a vertical axis and arranged to hold the articles that are to be washed or dried, during the operation of the machine. The cylinder is formed with perforated side 90 walls 8 and a bottom end wall 9 which are spaced from the side walls 12 and bottom plate 13 of the tank respectively. The upper end of the cylinder is formed open so that the clothes or dishes to be operated 100 upon may be readily inserted into or removed from the cylinder at this end.

Means are provided for causing practically all of the cleansing liquid to enter the cylinder adjacent the axis of rotation thereof. In this manner during the rotation of the cylinder each particle of liquid therein may attain the greatest possible centrifugal force for a given speed and diameter of the cylinder by the time said particles reach the 110

rim or side walls 8 thereof; therefore since during the rotation of the cylinder the clothes therein adhere to the rim and since as is well known the cleansing of the clothes depends to a great extent upon the force with which the liquid is drawn through them, the efficiency permitted by a cylinder constructed in accordance with my invention will be readily apparent. In accordance with the foregoing the end wall 9 preferably at its center, is formed with an orifice 14 through which the liquid from the tank is drawn into the cylinder. Arranged within the cylinder over the orifice 14 and extending upwardly practically to the top thereof is a tubular conduit 16 through the perforations 17 of which the liquid entering the orifice passes directly into the cylinder. As will be noted by referring to Figure 1 the liquid after being forced through the clothes and walls 8 passes downwardly in the tank between the tank and cylinder's side walls, and thence along the tank bottom into the conduit 16. It will thus be seen that the liquid has a comparatively smooth and unobstructed path, and since the perforated conduit extends practically the full length of the cylinder, the liquid will be distributed uniformly throughout the latter.

In the present embodiment of the invention the cylinder is adapted to rotate at two different heights with respect to the tank; at the lower height or position, which it is shown occupying in Figure 1, the cylinder is adapted to be immersed in the cleansing liquid so that the washing operation may be effected; in the upper position however, the cylinder is withdrawn from the liquid so as to permit the drying operation, the cylinder in the latter position being arranged to rotate at a very much greater speed than in the former. Suitable means are therefore provided for properly suspending the cylinder, moving it to the different positions, rotating it at the proper speeds, and other more or less necessary mechanism which will be hereinafter described.

Fixed to the upper end of the cylinder and conduit by a web 17 or other suitable means is a shaft 18 provided at its upper extremity with a flange 19 which engages a bearing member 21 formed at the lower end of a spindle 22. The latter is slidably held in the spider 5 arranged over the tank opening 3, and is formed with a toothed edge or rack 23 which is engaged by a segmental gear 24 also mounted on spider 5. Secured to the shaft 26 of the gear is a handle 27 by which the gear may be rotated to effect the raising or lowering of the spindle and depending mechanism. The spindle is further provided with a pair of vertically spaced notches 28 and 30 which are adapted to be engaged one at a time by a suitable locking member, such as the spring pressed dog 29,

in order to lock the cylinder in its upper or lower position.

The cylinder is held against lateral displacement at its lower end by means of an arbor 31 which is secured to the tank bottom 70 and journaled in a bearing 32 supported in the conduit 16. Fixed to the shaft 18 are a pair of bevel gears 33 and 34 which are spaced apart vertically so that they may mesh with pinion gears 36 and 37 respectively when the cylinder is in the drying or washing position as the case may be. The gear 34, with which the cylinder is rotated when the latter is in its drying position, is considerably smaller than the gear 33 with 80 which the cylinder is rotated in the washing operation, thereby enabling the cylinder to rotate at a comparatively high rate of speed during the drying operation.

Means are provided for arresting the rotation of the cylinder, as it is being moved from one position to another, in order that when the respective sets of gears are about to be placed in engagement with each other there will be no relative rotative movement 90 between them. As here shown the cylinder is provided with an annular band 38, preferably formed of a somewhat resilient material, which is adapted to be frictionally engaged by the relatively stationary spring arms 39 when the cylinder is moved from one position to another. The arms 39 are preferably curved as indicated in Figure 1 so that the rotative movement of the cylinder may be arrested gradually.

The pinion gears 36 and 37 are fixed on a shaft 41 mounted in a frame 42 which is suitably secured to the tank. The shaft 41 preferably extends through the wall of the tank and is connected by a belt 44 and pulleys 45 and 46 to the shaft 48 of a motor 49.

Means are also included for causing the cylinder rotating means to be impelled only when the cylinder properly occupies either 110 the washing or drying position. Preferably formed in conjunction with the locking dog 29 is a switch 51 suitably arranged in the motor circuit 52. The switch is provided with two terminals 53 and 54 which can only 115 be bridged by an insulated conductor 55, provided on the dog when the latter is engaged in one of the locking notches provided in the spindle 22.

To change the cylinder from the washing 120 to the drying position it is only necessary to withdraw the dog 29 from the notch 28, rotate the handle 27 so as to raise the cylinder until the dog is permitted to enter the notch 30. To move the cylinder from the 125 drying to washing position it is merely necessary to manipulate the said members in the reverse order.

Should it be desired to use the machine for the purpose of washing dishes or the like a 130

suitable rack 56 may be removably placed within the cylinder. The rack as here shown is formed in segmental sections 57, 58, 59, and 60, in order that the rack may be readily inserted in the cylinder. The sections are indicated by dotted lines in Figure 2.

I claim:

1. In a machine of the class described, a cylinder adapted to rotate about a vertical axis, means for moving said cylinder vertically to occupy different predetermined positions, means for rotating said cylinder in said positions, and electrical connections for said rotating means adapted to be held in operatively disposed when said cylinder is removed from said positions.
2. In a machine of the class described, a cylinder adapted to rotate about a vertical axis and to be moved axially to occupy different positions, means for rotating said cylinder in said positions, electrical connections for said rotating means adapted to be held inoperatively disposed when said cylinder is removed from said positions, and means for arresting the rotation of said cylinder as it moves from one of said positions to another.
3. In a machine of the class described, a tank, a cylinder arranged in said tank and adapted to occupy different predetermined positions, with respect thereto, means for rotating said cylinder in said positions, a source of electric power for actuating said rotating means, and means for simultaneously locking said cylinder in said positions and operatively connecting said rotating means with said source of power.
4. In a machine of the class described, a tank, a vertically disposed spindle slidably supported therein and provided with a pair of vertically spaced locking portions, a cylinder arranged in said tank and rotatably suspended from said spindle, a locking member, means for moving said spindle vertically whereby said locking member may engage in one or the other of said locking portions, driving connections for said cylinder whereby it may be rotated at a higher speed in its upper position than in its lower one, a source of electric power for actuating said driving connections, and electrical connections cooperating with said locking member whereby said driving connections will be unactuated except when said locking member is engaged in one of said locking portions.
5. In a machine of the character described, a tank, a cylinder arranged in said tank and

adapted to be moved vertically with respect thereto, an anti-friction bearing member adjacent the upper portion of said tank from which said cylinder is suspended for rotation about a vertical axis, a tub concentrically arranged within and fixed to said cylinder, a shaft extending upwardly into said tube and bearing therein, and means for rotating said cylinder.

6. A machine of the class described comprising a tank in which the cleansing liquid is adapted to be contained, a cylinder arranged in the tank and rotatable about a vertical axis, means for holding the cylinder suspended in the tank at different heights, means for rotating the cylinder at a greater speed in one position of suspension than in another, means for retarding the speed of rotation of the cylinder as it is moved from one position to another, means for moving the cylinder from one position to another, and means for locking the cylinder when properly positioned and for causing said cylinder rotating means to be driven only when the cylinder is so positioned.

7. In a machine of the character described, a tank, a cylinder arranged in said tank, a bearing from which said cylinder is suspended for rotation about a vertical axis, driven wheels of different size fixed for rotation with said cylinder, a driving member, and means for moving said cylinder and wheels axially whereby said driving member may alternately engage said driven wheels.

8. In a machine of the character described, a tank, a cylinder arranged within said tank, an anti-friction bearing from which said cylinder is supported for rotation about a vertical axis, means for moving said bearing vertically to vary the position of said cylinder with respect to the tank, a drive member, a pair of different sized driven wheels fixed for rotation with said cylinder adapted to be alternately engaged by said drive member as said cylinder is moved from one position to another, and motive means for said drive member adapted to actuate said member only when one of said wheels is engaged therewith.

In testimony whereof, I have hereunto set my hand at Oakland, California, this 1st day of November, 1920.

ARTHUR C. WHEELOCK.
